UNITED STATES PATENT OFFICE.

ALBERT L. OVERHOLT, OF MINNEAPOLIS, MINNESOTA, ASSIGNEE, BY MESNE ASSIGNMENTS, TO STEINER SALES COMPANY, OF SALT LAKE CITY, UTAH, A CORPORATION OF UTAH.

LOCK DEVICE FOR TOWEL CABINETS.

Application filed April 10, 1922. Serial No. 551,399.

To all whom it may concern:

Be it known that I, ALBERT L. OVERHOLT, a citizen of the United States, resident of Minneapolis, county of Hennepin, State of Minnesota, have invented certain new and useful Improvements in Lock Devices for Towel Cabinets, of which the following is a specification.

In towel cabinets using a continuous towel web, provision is made for measuring or delivering a predetermined length of towel with each pull of the user, the measuring device automatically resetting itself to allow the pulling and measuring operation to be repeated.

In some instances it is desirable to have the measuring device remain in its locking or checking position until released by the next or subsequent user, a trip device being provided which must be actuated by the user before delivery of the clean towel can be obtained.

The object of my present invention is to provide a mechanism in connection with the towel measuring device which will automatically assume a locking position when a predetermined length of towel has been delivered and prevent the measuring device from returning to its initial position until released or tripped by the person desiring to use the towel. Economy in the use of the towel is effected with such a device, as frequently there will be a considerable clean area on the towel that has been pulled down for use by one person and this clean area may be sufficient for the use of the next person and he either will not attempt to pull down a clean section of the towel, or, finding that it is locked, will not take the trouble to operate the release device or may not understand it sufficiently to operate it and will be satisfied with the use of the towel section which has previously been pulled down and partially used.

The invention consists generally in various constructions and combinations, all as hereinafter described and particularly pointed out in the claims.

In the accompanying drawings forming part of this specification,

Figure 1 is a vertical sectional view on the line 1—1 of Figure 3,

Figure 2 is a view corresponding to Figure 1, showing the measuring device moved to its locking position.

Figure 3 is a sectional view on the line 3—3 of Figure 1.

Figure 4 is a sectional view on the line 4—4 of Figure 1.

Figure 5 is a sectional view on the line 5—5 of Figure 7.

Figure 6 is a sectional view on the line 6—6 of Figure 7.

Figure 7 is a sectional view on the line 7—7 of Figure 5.

Figure 8 is a sectional view on the line 8—8 of Figure 5.

In the drawing, 2 represents the casing of the cabinet having a suitable door 3 through which access may be had to the interior. In the upper portion of the cabinet is a shelf 4 whereon the roll of clean toweling 5 is placed. A rod 6 is provided in the casing in the rear of the roll 5 over which the towel web passes and from thence down to the lower portion of the cabinet and under similar rods 7 arranged preferably one in front of the other on substantially the same level. From these rods 7 the towel web passes to a dispensing roll 8 having a roughened surface 9 of rubber, sand-paper or other suitable material. From this dispensing roll the clean towel depends through an opening 10 in the bottom of the casing to a point within convenient reach of the user.

Beneath the dispensing roll I provide vertical guideways 11 in the side walls of the casing, wherein a bar 12 is adapted to slide, the upper edge of the bar preferably being beveled slightly, as indicated at 13, for contact with the peripheral surface of the dispensing roll. Hubs 14 are provided at the ends of the dispensing roll and flexible means, such as chains 15, are attached at one end to these hubs and at the other end to the bar 12 so that when the dispensing roll is rotated or oscillated by the pull of the towel thereon, the bar 12 will be raised vertically in the guideways into contact with the surface of the dispensing roll to check its rotation when a predetermined length of towel has been delivered. Upon the release of the towel web, the weight of the bar 12 will carry it back to the bottom of the guide.

ways, rotating the dispensing roll so that it will automatically assume its normal position for allowing an additional delivery of the towel web.

For the purpose of holding the locking bar in its locking position, I provide a latch 16, pivotally supported at 17 and having an end 18 that is adapted to move in under the locking bar and hold it in its locking position. A spring 19 normally tends to hold the latch under the locking bar. As shown in Figure 1, the latch normally projects across the path of the bar 12 and is pushed away as the bar is raised and as soon as the bar has passed the latch, it swings back to its normal position, preventing the return of the bar until the latch is again operated.

For tripping the latch I provide a plunger 20 mounted in an arm 21 which normally limits outward movement of the lower end of the latch, but allows it to be pushed inwardly to move its upper end out of the path of the locking bar.

In Sheet 2 of the drawings, I have shown a modified construction which consists in substituting a single roll 22 for the rods 7 and providing a yoke 23 pivoted at 24 and adapted to swing upwardly against the dispensing roll, being connected therewith in the same manner as described with reference to Figure 1 for the purpose of preventing oscillation of the roll and feed of the towel. A pin 25 is provided on one of the side arms of the yoke and a latch 26 is pivoted at 27 near the bottom of the casing and has an upper end 28 that is adapted to engage the pin 25 and lock the yoke in its raised position, the upper end of the latch being angled slightly so that it is pushed out of the way of the pin 25 when the yoke is raised and will swing back under the pin to lock the yoke. A rod 29 is pivotally connected with said latch and projects through the wall of the casing in position to be actuated by the user, and has a stop 30 for limiting its outward movement and a spring 31 which normally tends to draw the rod and the latch toward the front of the cabinet and resist the pressure of the pin 25 when it pushes the latch out of its path on the upstroke of the yoke.

The normal position of the parts is illustrated in Figure 5, while in Figure 6, the locking position assumed by the yoke when the user has pulled down on the clean towel and the latch has engaged the pin 25, is shown, locking the yoke in contact with the surface of the dispensing roll. This contact will continue until the next user operates the rod 29, against the tension of the spring 31 and disengages the latch from the yoke pin. When this takes place, the yoke will drop by gravity to the position shown

in Figure 5, rotating the dispensing roll and setting the parts in position to allow a further measuring and delivering of the towel web when a pull is applied thereto.

In using the cabinet, the person desiring a section of clean towel will grasp the depending portion and pulling thereon, will oscillate the dispensing roll and the clean towel will be delivered through the opening in the bottom of the casing. As the roll turns, the sliding bar will be raised and at the limit of its upward movement will contact with the towel web and force it against the peripheral surface of the dispensing roll, clamping the web thereon and positively preventing further feed of the towel and rotation of the roll. At the same time, the locking latch will swing in under the bar and prevent it from sliding down the guideways when pull upon the towel ceases. The towel web will therefore be automatically locked when the first user has finished with the towel. The next person using the towel must either trip the locking latch first and allow the stop bar and roll to return to their normal position, or he must use the section of towel that has already been delivered. If he prefers to do this, or does do it, not understanding, perhaps, the manner of operating the release, a saving will be effected in the use of the towel. This saving is often of considerable importance to the owners of a building where the cabinet is installed. It is possible, of course, for any user that does desire a clean section of the towel to immediately obtain it by operating the latch, releasing the locking device and thereby allowing the dispensing roll to be again rotated to deliver a clean portion of the towel, but the necessity for releasing the roll will often cause a user to find a clean spot on the towel section already pulled rather than go to the trouble of operating the trip mechanism before another section can be pulled off the roll.

I claim as my invention:

1. A towel holder comprising a support for a roll of clean toweling, a dispensing roll over which the towel web passes and a measuring device including a bar movable into and out of engagement with the towel web on the roll and connected with said roll and actuated thereby for clamping the towel web on the surface of the roll and checking the rotation thereof at a predetermined point.

2. A towel holder comprising a support for a roll of clean towel, a dispensing roll over which the towel web passes, a measuring device including a bar movable into and out of engagement with the towel web on the roll and having flexible connections with said roll to be actuated thereby to check

rotation of said roll and deliver the towel when a predetermined length has been dispensed.

3. A towel holder having a support for a roll of clean towel, a dispensing roll over which the web of clean towel passes, a measuring device having flexible connections with said dispensing roll, guides wherein said measuring device is slideable, said device contacting with the towel web and roll for limiting the feed when a predetermined length has been dispensed.

4. A towel holder having a support for a roll of clean towel, a dispensing roll over which the web of clean towel passes, a measuring device having flexible connections with said dispensing roll, guides wherein said measuring device is slideable, said device contacting with the towel web and roll for limiting the feed when a predetermined length has been dispensed, said measuring device returning by gravity to its normal position when pull upon the towel ceases.

5. A towel holder comprising a support for a roll of towel, a dispensing roll over which the web of clean towel passes, a sliding bar having flexible connections with said dispensing roll to be moved by the rotation thereof into contact with the towel web and roll for checking movement of said roll when a predetermined length of towel has been dispensed.

6. A towel holder comprising a support for a roll of towel, a dispensing roll over which the web of clean towel passes, said roll having hubs at the ends thereof, a bar slidably mounted and having flexible connections at its ends with said hubs, rotation of said dispensing roll winding said flexible connections on said hubs and drawing said bar into contact with the towel web and roll to check the dispensing of the clean towel web.

7. A towel holder comprising a support for a roll of clean towel, a dispensing roll over which the towel web passes, a measuring device connected with said roll to be actuated by the rotation thereof and drawn into contact with said roll to check delivery of the clean towel, and a latch device mounted to lock said measuring device in its checking position.

8. A towel holder comprising a support for a roll of clean towel, a dispensing roll over which the towel web passes, a measuring device connected with said roll to be actuated by the rotation thereof and drawn into contact with said roll to check delivery of the clean towel, a latch mounted in the path of said measuring device for engaging and holding said measuring device in its checking position, and means within the reach of the user for tripping said latch device.

9. A towel holder comprising a support for a roll of clean towel, a dispensing roll over which the towel web passes, a measuring device connected with said dispensing roll and actuated thereby to be drawn into contact with said roll to check its rotation, a latch mounted in the path of said measuring device for engaging and holding said measuring device in its checking position, and a plunger connected with said latch device.

10. A towel holder comprising a support in the upper portion thereof for a roll of clean towel, guide means around which the web of clean towel passes, a dispensing roll beneath and near the towel roll and over which the clean towel web is carried, an opening being provided in the lower portion of said holder through which the clean web is fed to the user, and a measuring device actuated by the movement of said dispensing roll for clamping the towel web thereon and checking the feed.

11. A towel holder comprising a support in the upper portion thereof for a roll of clean towel, guide means around which the web of clean towel passes, a dispensing roll beneath and near the towel roll and over which the clean towel web is carried, an opening being provided in the lower portion of said holder through which the clean web is fed to the user, and a measuring device actuated by the movement of said dispensing roll for clamping the towel web thereon and checking the feed, and means for holding said checking device in its checking position.

In witness whereof, I have hereunto set my hand this 6th day of April, 1922.

ALBERT L. OVERHOLT.
